THERMAL EXPANSION RESPONSIVE CONTROL

Loerwood C. Wasson, Wauwatosa, Wis., assignor
to Milwaukee Gas Specialty Company, Milwaukee,
Wis., a corporation of Wisconsin

Application July 15, 1943, Serial No. 494,798

3 Claims. (Cl. 297—4)

This invention relates to thermal expansion responsive controls of the type used to effect closure of the safety valve of a gas fired furnace upon extinction of the pilot light. Such controls generally comprise a bellows type expansion chamber connected with a temperature sensitive expansion bulb and arranged to actuate a controlling member in accordance with temperature changes at the bulb.

In the past, where controls of this type have been used on safety valves of gas fired furnaces, the bulb or temperature sensitive element was responsive to ambient temperature as well as the pilot flame of the gas burner so that in some instances the valve would not be released for closure even though the pilot light was extinguished. In any event the response was objectionably slow.

In other words, if the temperature in the burner chamber, i. e., the ambient temperature, is quite high, control devices of the past were slow to respond as the burner chamber temperature might be sufficiently high to hold the valve open for an appreciable time notwithstanding the extinction of the pilot flame.

It is therefore an object of this invention to provide a control device of the character described, the functioning of which is not dependent upon ambient temperature, but solely upon the temperature differential between the direct heat of the pilot flame and the ambient temperature. Hence, with the present invention, extinction of the pilot flame is quickly followed by release of the valve for closure.

In a broad general way, this invention achieves its objective through the provision of a pair of opposed bellows type expansion chambers having their movable ends connected with the latch or other member through which the controlling function is accomplished in such a way that expansion of these chambers applies opposed forces on the latch or controlling member, and through the further provision of separate temperature sensitive expansion bulbs, one connected with each of the expansion chambers, and with one of the bulbs in juxtaposition to the pilot flame and the other spaced therefrom.

Another object of this invention resides in the novel construction of the expansion chambers whereby one is substantially nested within the other to conserve space and to reduce the volume of the outer chamber.

Still another object of this invention is to provide an improved and simplified manner of constructing the temperature sensitive bulbs and

connecting the same with their respective expansion chambers.

With the above and other objects in view which will appear as the description proceeds, this invention resides in the novel construction, combination and arrangement of parts substantially as hereinafter described, and more particularly defined by the appended claims, it being understood that such changes in the precise embodiment of the herein disclosed invention may be made as come within the scope of the claims.

The accompanying drawing illustrates two examples of the physical embodiment of the invention constructed in accordance with the best modes so far devised for the practical application of the principles thereof, and in which:

Figure 1 is a view in side elevation illustrating a safety valve for a gas burner equipped with a control device embodying this invention;

Figure 2 is an enlarged vertical sectional view through the valve and the control mechanism illustrating the manner in which the valve is latched open;

Figure 3 is a detail view partly in side elevation and partly in section illustrating the temperature sensitive compound bulb of the control device; and

Figure 4 is a view similar to Figure 3 illustrating a slightly modified construction for the compound bulb.

Referring now particularly to the accompanying drawing, in which like numerals indicate like parts, the numeral 5 designates a gas burner or the like to which fuel is fed through a supply pipe

6. The supply pipe has a safety valve 7 incorporated therein, the valve disk 8 of which is biased to closed position by a spring 9 and adapted to be lifted to open position by a push button 10.

The body of the valve is substantially a T fitting and has the control device indicated generally by the numeral 11 mounted in its stem. The control device is contained with a bonnet 12 secured to the stem of the T with a fluid tight junction by a clamping nut 13.

A cup-shaped member 14, held in place by the attachment of the bonnet 12, extends into the stem of the valve body to provide a guide for the stem 15 of the valve disk. The upper end of the stem 15 is received in a pilot bore 16 extending up into an arm 17 projecting in from the side of the bonnet. This arm 17 provides support for a pivotally mounted latch 18, the free end of which is hook-shaped to engage in a slot 19 in the valve stem and hold the valve open against the force of its spring 9.

The latch 18 is controlled by a pair of expansion chambers 20 and 21, both of the bellows type, the latter being nested wholly within the former. The expansion chamber 20 has its fixed or stationary end secured to the top of the bonnet as at 22 and has a cylinder 23 fixed in its movable end. The cylinder 23 provides a well in which the smaller expansion chamber 21 is received.

This smaller chamber comprises two bellows, one within the other, having a common movable end 24 fixed to the inner end of the cylinder 23. The opposite stationary ends of the two bellows of the chamber 21 are fixed to a central duct 25 which has openings 26 leading to the interior of the small expansion chamber 21.

A disk or other bridging member 27 fixed to the movable end of the bellows forming the chamber 20 and to the cylinder 23 is connected, as at 28, to the pivoted latch 18. Holes 29 in the disk 27 permit free passage of air, gas or other fluid into and out of the well formed by the cylinder 23 to preclude interference with expansion and contraction of the chamber 21.

The tube 25 to which the stationary or fixed end of the small expansion chamber is secured is fixed in relation to the stationary end of the large expansion chamber 20 and has open communication with a duct 30 which leads to and is connected with an expansion bulb 31.

Surrounding the duct 30 is a tube or duct 32 which is likewise fixed with relation to the stationary end of the expansion chamber 20 and has open communication with the interior of this expansion chamber through ports 33. This outer duct leads to and connects with an expansion bulb 34.

It is to be observed that the annular space between the two tubes or ducts provides a capillary passage connecting the expansion bulb 34 with the expansion chamber 20 and that the inner tube or duct 30 provides a capillary passage connecting the bulb 31 with the expansion chamber 21.

The bulbs may be arranged one within the other, as shown in Figure 3, or they may be constructed as illustrated in Figure 4.

The arrangement of Figure 3, wherein the bulb 31 is insulated from ambient temperature by being enclosed within the bulb 34 upon which the pilot flame plays results in more rapid response while the construction shown in Figure 4 is preferable from the standpoint of simplified mechanical design as the telescoping juncture 35 between the bulbs 31' and 34' facilitates assembly of the unit.

With the bulb construction shown in Figure 4, the pilot flame plays on the lower bulb chamber 34' thus leaving the upper bulb chamber 31' exposed to the ambient temperature. However, this latter bulb 31' is sufficiently close to the pilot flame to receive considerable heat therefrom by conduction so that it becomes heated to a substantial degree above ambient or burner chamber temperature.

While, as noted hereinbefore, the construction shown in Figure 3 results in more rapid response than that of Figure 4, both arrangements are far superior to past practice as in each case it is the temperature differential at the two bulbs and not the ambient temperature at a single bulb that controls the release of the valve. Whether the bulb construction of Figure 3 or Figure 4 is employed, extinction of the pilot flame is followed by a more rapid contraction of the bellows forming the larger outer chamber 20 than

takes place in the smaller chamber 21. Consequently, the contraction of the bellows 20 and the still effective expansion force of the chamber 21 produce an additive effect on the latch to quickly retract it from the slot in the valve stem.

The expansion chambers and the bulbs connected thereto may be filled with any suitable fluid medium, air being satisfactory for the purpose to which this invention is especially directed, namely the control of a safety valve for gas fired furnaces and the like.

Operation

Assuming that the safety valve is closed and the pilot light extinguished: under these circumstances a state of equilibrium exists between the expansion chambers 20 and 21. The spring tension of the large outer chamber 20, which applies an upward force on the latch in opposition to the downward force applied by the spring tension of the lighter and smaller expansion chamber 21, effects a resultant upward force on the latch to hold the same free from the valve stem 15. In this, the spring tension of the bellows may or may not be augmented by a spring 36 depending upon the tension inherent in the bellows.

To set the mechanism in operation the pilot light is ignited so that its flame plays on the temperature sensitive bulb 34 (or 34') if the construction of Figure 4 is used). The fluids in the two bulbs 34 and 31 are thus expanded to effect expansion of the chambers 20 and 21.

By virtue of the higher temperature at the bulb 34 (or 34') the fluid therein is expanded to a higher pressure than in the bulb 31 (or 31'). The force of expansion of the chamber 20 thus exceeds that of the chamber 21 to impart a downward thrust on the latch 18. This downward thrust on the latch holds its hooked end against the side of the valve stem making it potentially operative to engage in the slot 19 and hold the valve open upon manual setting of the valve by depression of the push button 16.

As long as the pilot flame burns the valve is held open by the latch. Upon the extinction of the pilot flame, the bulb 34 cools more rapidly than the bulb 31 so that the force of expansion within the chamber 20 decays more rapidly than the expansion force of the chamber 21. The rapid decadence of the expansion in the chamber 20 is additive with the relatively still prevalent expansion force of the chamber 21 thereby bringing about a rapid withdrawal of the latch 18 from the slot 19.

In this respect, as noted hereinbefore, the tension applied on the latch by the inherent tension of the expansion chamber 20 may be augmented by the auxiliary spring 36.

In any event, due to the opposed relationship of the expansion chambers and the differential in their pressure areas, release of the valve is effected within a relatively short time after extinction of the pilot light regardless of what the ambient (burner chamber) temperature at the bulbs may be.

From the foregoing description taken in connection with the accompanying drawing, it will be readily apparent to those skilled in the art that this invention provides a substantial improvement in thermal expansion control devices through its elimination of dependency upon ambient temperature and the resulting rapid and positive response effected thereby.

What I claim as my invention is:

1. In a thermal expansion responsive control of the character described, a thermal sensitive element comprising: a compound bulb having two compartments; and ducts, one within the other, for connecting the two compartments separated by a metal wall common to both so that fluid in both compartments may be heated from the same heat source, one by direct application of heat on its compartment and the other by conduction through said common metal wall of the 10 compound bulb with separate expansion chambers.

2. In a control device of the character described: two expansion chambers, one within the other; a compound temperature sensitive bulb having two separate compartments, one within the other so that fluid in the outer compartment may be heated by the direct application of heat on its wall, while fluid in the inner compartment is heated indirectly from the same heat source by the fluid in the outer compartment; and duct means, one within the other, for connecting each compartment with one of said expansion chambers.

3. A thermal expansion responsive control for 25

the safety valve of a gas fired furnace for effecting closure of the safety valve upon extinction of the pilot light of the furnace comprising: a movable member operable to effect the desired controlling function; a pair of expansion chambers each having a movable end and a fixed end; means connecting the movable ends of said expansion chambers with said member so that the forces of expansion of said chambers are applied on said member, but in opposite directions; a compound temperature sensitive bulb having two fluid compartments separated from each other by a metal wall so that the temperature of the fluid in one compartment may be effected by the temperature of the fluid in the other compartment; means mounting said compound temperature sensitive element so that the direct flame of the pilot light plays on one of said compartments to directly heat the fluid therein and indirectly heat the fluid in the other compartment; and ducts, one within the other, connecting each compartment of the compound temperature sensitive bulb with one of the expansion chambers.
